US00D994695S

(12) **United States Design Patent** (10) **Patent No.:** **US D994,695 S**
(45) **Date of Patent:** **** Aug. 8, 2023**

(54) **DISPLAY SCREEN OR PORTION THEREOF WITH GRAPHICAL USER INTERFACE FOR CONTINUOUS GLUCOSE MONITORING**

(71) Applicant: **ABBOTT DIABETES CARE INC.**, Alameda, CA (US)

(72) Inventors: **Gary A. Hayter**, Oakland, CA (US); **Timothy C. Dunn**, San Francisco, CA (US); **Nathan Crouther**, San Francisco, CA (US); **Daniel M. Bernstein**, El Granada, CA (US); **Eric L. Davis**, Castro Valley, CA (US)

(73) Assignee: **ABBOTT DIABETES CARE INC.**, Alameda, CA (US)

(**) Term: **15 Years**

(21) Appl. No.: **29/803,597**

(22) Filed: **Aug. 13, 2021**

(57) **CLAIM**

The ornamental design for a display screen or portion thereof with graphical user interface for continuous glucose monitoring, as shown and described.

DESCRIPTION

The FIGURE is a front view of a display screen or portion thereof with graphical user interface for continuous glucose monitoring showing our new design.

The outer perimeter illustrated by dashed broken lines in the FIGURE illustrates a display screen or portion thereof and forms no part of the claimed design. The remaining dashed broken lines in the figure illustrate portions of the graphical user interface that form no part of the claimed design.
